UNITED STATES PATENT OFFICE.

GEO. P. SANBORN AND WILLIS MANSFIELD, OF NEW HAVEN, CONNECTICUT.

ELASTIC RAILROAD-FROG.

Specification of Letters Patent No. 24,664, dated July 5, 1859.

To all whom it may concern:

Be it known that we, GEORGE P. SANBORN and WILLIS MANSFIELD, of New Haven, Connecticut, have invented a new and useful Elastic Railroad-Frog, and that the following specification, taken in connection with the drawings, is a full, clear, and exact description thereof.

In the drawings: Figure first is a perspective view of the frog—Fig. second is a longitudinal section through the center thereof—Fig. third is a cross section through the point of the frog—and Fig. fourth is a plan of the bottom plate of the frog showing the bolts.

Frogs for railroads at the present time are usually made of cast iron with wrought iron or steel points, and are liable to many objections which are well known to railroad engineers and machinists, one of the chief defects being the rigidity, which causes heavy jars to the cars and locomotives whose wheels run through the frog. When the cast iron frogs become worn they cannot be repaired and must be replaced by new ones.

By our invention the evils arising from the rigidity or unyielding quality of the ordinary frog are remedied and our frog can be more easily handled and adjusted than the old one, is little if any more costly and its wearing parts can be removed and replaced with ease, and to accomplish this it is made up of layers of wood and iron bolted to each other with layers of india rubber interposed, if deemed desirable.

The best construction of frog according to the principles of our invention that we know of, and one that has been used with much success in experimental practice is represented in the drawings, and is made as follows:

A sheet of boiler plate, or heavy wrought iron of proper size is first procured and has drilled or punched through it proper holes for bolts and also for spikes to secure the frog to cross ties if thought desirable. Upon this plate is laid one of wood and upon that again one of vulcanized india rubber and then another plate of iron, all as clearly shown in the drawings. Above this second iron plate is another plate or layer of wood which is surmounted by a third plate of sheet iron, and on top of this last plate of sheet iron are laid the stem of

the frog, as shown at *a*, and the jaws of the frog which form the continuation of the rails, as shown at *b b*.

The stem and jaws are drilled for bolt holes with countersunk heads, and bolts are passed down through these holes and their continuations in the various layers of iron, wood, and india rubber and secured by nuts or in any other proper way under the lowest plate of all.

Additional bolts for fastening the various layers together, such as are shown in the drawings may be used if necessary. The point of the frog, shown at *c*, needs the firmest attachment; we therefore cut a slot through both the uppermost iron and wooden plates and drop the point into the slot, so that its bottom or lower face rests upon the second iron plate from the top (see the two sectional figures in the drawings). By such a construction the point is held more firmly than if it depended only upon the bolts that pass through it.

The uppermost iron plate may be slotted at the ends, and the uppermost wooden plate cut away as shown in the drawings so as to form chairs for the ends of the rails, which will always secure a proper alinement of the rails with the frog. Now the india rubber may be dispensed with or more layers of india rubber may be introduced, and the number of layers of wood or iron may be increased or diminished and the frog still constructed in accordance with our invention, as we do not deem the precise number of layers, a matter of importance, although we believe the number and arrangement as shown, to be the best. The point also may rest upon the uppermost iron plate and be fastened by bolts only, and the rails may be held in proper alinement with the frog by other modes than that shown in the drawings.

A careful examination of the frog will show that it has elasticity both in vertical and horizontal planes, the former being due to the elasticity of the materials and the fact that they are disposed in layers, each one of which is thin when compared with the whole thickness of the frog; and the latter to the same cause, and the elasticity of the bolts, and the slight play they have in the bolt holes. It is also evident that the frog may be constructed cheaply and that

it is much lighter, easier to handle, and to adjust than the ordinary cast iron frogs.

We claim as of our own invention—

1. An elastic frog constructed of layers 5 of plate metal and wood substantially in the manner specified and either with or without layers of vulcanized rubber.

2. And also we claim constructing an elastic frog with end slots suitable to receive the lower flange and neck of a rail, as

specified, whereby the frog may be kept in alinement as described.

In testimony whereof we have hereunto subscribed our names on this 30th day of April A. D. 1859.

GEO. P. SANBORN.
WILLIS MANSFIELD.

In presence of—

W. E. WORTHEN,
JOHN AVERY, Jr.
